UNITED STATES PATENT OFFICE.

KRIKOR S. GARA-MAGHDESIAN, OF NEWBURYPORT, MASSACHUSETTS.

SHOE AND PROCESS OF MAKING SHOES.

1,261,802.

Specification of Letters Patent. Patented Apr. 9, 1918.

Application filed January 18, 1917. Serial No. 142,979.

To all whom it may concern:

Be it known that I, KRIKOR S. GARA-MAGHDESIAN, a subject of the Sultan of Turkey, residing at Newburyport, in the county of Essex and State of Massachusetts, have invented new and useful Improvements in Shoes and Processes of Making Shoes, of which the following is a specification.

10 This invention relates to improvements in shoes and in processes of making shoes. More particularly it relates to devices for improving the construction of shoe soles, and the attachment of the upper thereto. 15 The object of the invention is to reduce the cost and to improve the flexibility of the finished product. These objects are accomplished by the introduction of certain supporting elements with the edge parts of the 20 upper, at the ball of the foot, and by the omission of the inner sole at that place. In a shoe made according to the invention all that part of the inner sole which customarily lies forward of the shank may be 25 omitted. The lateral supports in the upper edges are applied soft, molded to desired form, hardened in place, and are used temporarily to hold the bottom edge of the upper stiff as an inner sole does while the outer 30 sole is being applied. The permanent holding is by the outer sole. These side supports are far less expensive than leather inner soles, because of their material, and they produce a shoe of greater flexibility, be- 35 cause of the absence of the inner sole at the place where the bending of the shoe mainly occurs in the act of walking. An ordinary shank extends forward from the heel in the usual location of the inner sole, for about 40 half of the total length of the shoe or a little less. In the process of manufacture, the upper is provided at the heel with the usual counter, and at the toe with the usual tip or box stiffener, between the lining and the 45 vamp. Two additional pieces of stiffening material are inserted between the lining and the vamp, one at each edge, extending longitudinally from the back of the tip to the forward end of the shank, and wide enough 50 transversely so that when the shoe is on the last they can each extend inward somewhat over the bottom, and upward a little at the side, forming an angle at the edge of the last. The various pieces of stiffening ma- 55 terial having been made temporarily pliable in the usual way, the shoe is lasted by se-

curing the shank to the bottom of the last and lasting the upper thereto; and tacking the edges of the upper forward of the shank directly to the last. After the stiffening 60 material has become dry and stiff again, the tacks which secure the front part of the upper to the last are removed and the outer sole is cemented directly to the inturned edges of the upper, throughout its length, 65 the shape of the forward part of the upper being meanwhile preserved by the said stiffened material. When the cement has set, the upper and the outer sole are stitched together by the usual process. For finishing the interior, a lining is cemented over the bottom, and, as the forward end of the shank was originally beveled, the shoe thus becomes smooth within.

An illustrative example of the working 75 of the process and of the product follows, in aid of which reference may be made to the accompanying drawings, in which—

Figure 1 is a side elevation of a shoe embodying the invention, partly in section;

Fig. 2 is a front elevation in section, of the shoe in process of manufacture, showing the stage in which the upper and sole are assembled and glued together on the last;

Fig. 3 is a similar elevation of the shoe completed, in section on the line 3—3 of Fig. 1;

Fig. 4 is a perspective view of a detail, the reinforcing piece, before being bent into its 90 angular shape;

Figs. 5 and 6 are views like Fig. 3 showing other embodiments.

Referring to the drawings, 10 indicates the upper, 11 the counter, 12 the shank, and 13 95 the tip or box toe of a shoe. The outer sole is marked 14. The shoe has no inner sole in the usual sense of that word, except that the shank 12 constitutes an inner sole so far as it extends. This shank underlies the heel and 100 instep of the foot in the completed shoe and has a beveled forward edge. In the process of making the shoe, the upper is prepared in the usual way, with insertion of the stiff counter 11 between the upper leather 10 and 105 its lining 15, and by insertion of the stiff tip 13 at the place where the box toe is to be, between the leather and the lining of the upper. A new step, characteristic of the invention, is taken when additional pieces 16 110 of stiffening material are inserted between the leather and lining of the upper at each

side of the bottom. These are each long enough to extend from the forward end of the shank to the rear end of the tip 13, and are each wide enough to extend up a little 5 way on the side of the foot between the upper and lining, and inward a little way from the side of the foot, with the inturned upper. The various pieces of stiffening material, the counter, tip and central supports 10 are of material which is normally somewhat stiff, but which can be made temporarily pliable, as by being moistened, and which stiffens again upon returning to its normal condition of dryness. After insertion 15 of the stiffeners in the upper the shank may be secured to the bottom of the last 17, and the upper lasted in the usual way, as far as the shank extends. The edges of the forward part of the upper, beyond where the shank 20 extends are tacked directly to the last, and are allowed to dry and to stiffen in the shape thus produced. Any necessary trimming is done at this time. The composite structure on the last by this means receives 25 a shape which is sufficiently secured as to all parts forward of the shank by the stiffened side supporting pieces 16, so that the shape is retained during such handling as is necessary in the further process of the shoe 30 manufacture, until the application of the outer sole has given greater resisting power. For this step of the process it may be noted that the stiffening pieces are angular in cross section so that the extent of the material 35 in either direction from the angle where the piece is bent serves somewhat as a strut to prevent the bending of the angular shaped piece, just as either flange of a bar of angle iron prevents its bending. For this reason 40 a relatively light and cheap stiffener 16, at each side of the sole, holds the inturned edges of the upper true to the shape that has been given them in the lasting operation. The heel and shank portions are held with 45 the same security which has always heretofore been characteristic of a lasted shoe; the toe portion is held by the stiffened tip, which prevents spreading, and the intervening portion, where the supports 16 are, is held 50 against a spreading because the forward end of each support 16 is close to the stiffly held rear of the tip, and the rear end of each support is close to the forward end of the shank where the upper is stiffly held by the 55 lasting. Hence, both ends of the supports 16 being fixed by the adjacent attachment of the upper to the tip and the shank, those ends can not move to distort the shoe; and as the supports themselves have become stiff 60 in their acquired shape, the leather intervening between their ends does not crinkle or otherwise lose the shape given to it upon the last. The outer sole may then be cemented to the inturned edges of the upper; and then, 65 being thus temporarily held in place, may

be stitched to the upper; after which the shoe may be finished as is usual. As the in-turned edges of the upper and the forward edge of the shank would be exposed to the wearer's foot, it is preferred to cover them 70 with a lining laid upon the sole in the interior of the shoe, thus making the inside of the shoe smooth.

The economy introduced into the processes of manufacture of shoes by this improvement results from the saving of material hitherto employed in the inner sole forward of its shank portion. The material employed in the side supports 16 may be relatively inexpensive, consisting either of leather or 75 preferably of fabric. For example, it may be such material as is customarily used for making box toe stiffeners. Very little of that material is required. The completed shoe has a degree of flexibility in the sole 80 which is enhanced by the absence of the customary inner sole in that part of the shoe where the bend comes at every step taken by the wearer. The new process of shoe manufacture thus described consequently has the 85 advantage both of reducing the cost of construction of shoes, and particularly of shoes of the lower grade, and also of increasing the comfort of such shoes. The latter permits McKay sewed shoes, which are typically 90 more stiff in their soles than other styles of shoes, to attain in a larger degree the comfort which is characteristic of the more expensive shoes, and in fact to approximate 95 that high degree of flexibility at the ball of 100 the foot, where flexibility is most important, which hitherto has been characteristic only of turned shoes and other single soled shoes. While I have illustrated my invention as applied to a shoe having a box toe it is not 105 limited to such shoes, as the side reinforcing strips may be caused to extend forward as far as their stiffening effect may be required.

In the practice of the process under commercial conditions variations may be made 110 from the specific illustration here given, within the scope of the appended claims; and it is intended that the patent shall cover, by suitable expression in these claims, whatever features of patentable novelty exist in 115 the invention disclosed.

Figs. 5 and 6 illustrate two different embodiments of the invention, showing its application to shoes having thicker soles. In each case there is in the sole an extra layer, 120 which may be leather or other suitable material, below that marked 14 which is next to the upper. This is marked 14' and in Fig. 5 is attached by causing the line of stitching which goes through the inturned edge of 125 the upper to go through both layers of the sole, as at 18'. In Fig. 6, the extra layer is attached by an extra line of stitching 19, running around the outside and not passing through the upper. This extra line of stitch- 130

ing 19 may also be used in addition to the line of stitching 18' as shown in Fig. 5.

I claim as my invention:—

1. A method of making shoes including the providing of an upper with flexible reinforcing strips along its edges at each side of the ball of the foot; lasting the upper to a shank extending from the rear to and terminating at said reinforcements; molding said reinforcements and said upper around the corner of the last; holding and permitting the strips to stiffen in the molded shape; and then fastening an outer sole to the strips and to the upper.
2. A method of making shoes including the providing of an upper and means to make its toe and heel portions stiff and flexible reinforcing strips along its edges at each side of the ball of the foot; lasting the upper to a shank extending from the rear to and terminating at said reinforcements; molding said reinforcements and said upper around the corner of the last; fastening them temporarily in the molded shape; permitting the strips to stiffen in the shape in which they are thus held; cementing an outer sole to the upper while on the last; and then stitching the outer sole thereto and to the strips while the edges of the upper are held by the cement.

3. A shoe comprising an upper, a shank in the position customarily occupied by the rear part of an inner sole, and an outer sole; the rear portion of the upper being lasted to said shank, and the forward portion of the upper having edges fastened directly to the outer sole; said edges containing stiffening supports on both sides of the ball of the foot, and said supports being angular in cross-section, with their inturned portions extending only along the edges of the sole. 40

4. A shoe comprising an upper, a shank in the position customarily occupied by the rear part of an inner sole, and an outer sole; the heel portion of the upper having stiffening material and being lasted to said shank, and the toe portion of the upper having stiffening material with edges fastened directly to the outer sole; and the intervening portion of the upper having stiffening material at its edges; said intervening stiffening material being angular in cross-section, with its inturned portion extending only along the edges of the sole. 45 50
